CLAIM

The ornamental design for a towable water sports equipment, as shown and described.

DESCRIPTION

FIG. 1 is a perspective view of the towable water sports equipment of the present invention showing my new design in grayscale;

FIG. 2 is a left side view thereof in grayscale;

FIG. 3 is right side view thereof in grayscale;

FIG. 4 is front view thereof in grayscale;

FIG. 5 is a back view thereof in grayscale;

FIG. 6 is a top plan view thereof in grayscale; and,

FIG. 7 is a bottom plan view thereof in grayscale.
